Primary Examiner — Bao-Yen T Nguyen*Assistant Examiner* — Christopher John Suarez La Rosa(74) Attorney, Agent, or Firm — Millen, White, Zelano & Branigan P.C.; Wan-Ching Montfort(57) CLAIM

The ornamental design for a box of storage shelf as shown and described.

DESCRIPTION

FIG. 1 is a top front perspective view of a box of storage shelf showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom front perspective view thereof.

The dashed broken lines in the figures show portions of the box of storage shelf that form no part of the claimed design.

1 Claim, 6 Drawing Sheets(56)
